UNITED STATES PATENT OFFICE.

HENRY HEITMANN, OF MIAMISBURG, OHIO.

DESIGN FOR A CIGAR.

SPECIFICATION forming part of Design No. 28,836, dated June 14, 1898.

Application filed May 2, 1898. Serial No. 679,543. Term of patent 3½ years.

To all whom it may concern:

Be it known that I, HENRY HEITMANN, a citizen of the United States, residing at Miamisburg, Montgomery county, State of Ohio, have 5 invented and produced a new and original Design for Cigars; and I do declare the following to be a clear, full, and exact description of the invention, such as will enable others skilled in the art to which it appertains to 10 make and use the same, reference being had to the accompanying drawings, forming a supplement to the description.

Figure 1 is a vertical elevation of a cigar made in accordance with my new design. 15 Fig. 2 is a cross-sectional view of the same.

As is shown in the drawings, the leading or material feature of my design consists in a cigar provided with a series of longitudinal ribs and grooves on each of its four sides to

the end that the same may have a distinctively ornamental appearance.

The ribs *a* and grooves *b* are disposed or arranged longitudinally and throughout the entire surface of the cigar. The latter is given a substantially rectangular form in cross-section, and each of the four corners forms one of the said ribs *a*.

Having described my design, I claim as new and desire to secure by Letters Patent—

The design for a cigar as herein shown and described.

In testimony whereof I hereunto affix my signature in the presence of two witnesses.

HENRY HEITMANN.

Witnesses:

FRANK. W. HOWELL,
R. J. McCARTY.
